UNITED STATES PATENT OFFICE.

SAM HARBISON, OF KNOXVILLE, TENNESSEE.

DESIGN FOR A TRACE-FASTENER SPRING.

SPECIFICATION forming part of Design No. 31,531, dated September 19, 1899.

Application filed August 12, 1899. Serial No. 727,072. Term of patent 14 years.

To all whom it may concern:

Be it known that I, SAM HARBISON, a citizen of the United States, residing at Knoxville, in the county of Knox and State of Tennessee, see, have invented and produced a new and original Design for a Trace-Fastener Spring, of which the following is a specification.

This invention relates to a new and original design for a trace-fastener spring; and it has for its object to provide a design of this character that shall be both useful and ornamental.

The leading feature of the design resides in a straight flat body-plate provided near one end with a laterally-projecting approximately U-shaped band and beyond the latter with an arched terminal tongue, the band in said terminal tongue being concavo-convex in cross-section, said flat body-plate being further provided at the end opposite the terminal tongue with a clip extension of a U shape in cross-section.

The minor features of the design are the terminal tongue of the body-plate being of a tapering width and the U-shaped clip extension having a rounded end ear disposed substantially within the longitudinal plane of the body-plate and a pair of duplicate rounded side ears bent from the side edges of the plate at approximately right angles thereto.

In the drawings, Figure 1 is a perspective view of a trace-fastener spring embodying the design contemplated by the present invention. Fig. 2 is a similar view with the

spring shown reversed. Fig. 3 is a cross-sectional view on the line 3 3 of Fig. 1. Fig. 4 is a similar view on the line 4 4 of Fig. 1.

Referring to the accompanying drawings, the numeral 1 designates the straight flat body-plate of the spring. This body-plate is provided near one end with a laterally-projecting approximately U-shaped bend 2 and beyond this bend with a longitudinal curved or arched terminal tongue 3, said terminal tongue, as well as the bend 2, being concavo-convex in cross-section, as plainly shown in Fig. 4 of the drawings. At the end opposite the terminal tongue 3 the flat body-plate 1 is further provided with a clip extension 4 of a U shape in cross-section, as shown in Fig. 3 of the drawings. The said clip extension 4 of the body-plate is provided with a rounded end ear 5, lying substantially within the longitudinal plane of the body-plate, and with a pair of duplicate round side ears 6, bent from the side edges of the plate at approximately right angles thereto.

What is claimed is—

The design for a trace-fastener spring herein shown and described. 60

In testimony that I claim the foregoing as my own I have hereto affixed my signature in the presence of two witnesses.

SAM HARBISON.
